United States Patent Office

Des. 224,294
Patented July 18, 1972

224,294

MOTEL OFFICE BUILDING

Howard L. Schwartz, Miami Beach, Fla., assignor to United Inns Mfg. Corp., Kansas City, Mo.

Filed May 3, 1971, Ser. No. 140,021

Term of patent 14 years

Int. Cl. D25—03

U.S. Cl. D13—1

*Fig. 3.Fig. 5.Fig. 4.*FIG. 1 is a perspective view of a motel office building embodying my design.

FIG. 2 is a plan view thereof.

FIG. 3 is a front elevational view thereof.

FIG. 4 is one side elevational view thereof.

FIG. 5 is an enlarged fragmentary sectional view showing a projection and roof contour at the sides and ends thereof.

I claim:

The ornamental design for the motel office building, as shown and described.
